UNITED STATES PATENT OFFICE.

HIRAM STEVENS MAXIM, OF LONDON, ENGLAND.

MERCURIAL AIR-PUMP.

SPECIFICATION forming part of Letters Patent No. 639,593, dated December 19, 1899.

Application filed April 28, 1899. Serial No. 714,821. (No model.)

To all whom it may concern:

Be it known that I, HIRAM STEVENS MAXIM, chevalier of the Legion of Honor, civil and mechanical engineer, a citizen of the United States, residing at 18 Queens Gate Place, London, in the county of Middlesex, England, have invented certain new and useful Improvements in Mercurial Air-Pumps, of which the following is a specification.

10 This invention relates to mercurial air-pumps, and especially to those of the kind known as the "Geissler" and the "Sprengel."

According to my present invention I provide the head—that is to say, the enlarged upper portion of the bent tube into which the mercury flows from a reservoir—with a hollow float, which is adapted to act as an automatic device for checking the inlet of the mercury to the said head when its flow through the pump 20 is unduly retarded or is stopped. The said hollow float is so constructed that the mercury, when its flow is not checked, will pass through the float in a finely divided or comminuted condition, whereby any air or gas 25 contained in the mercury will be effectually liberated, so as to be easily removed from the head by suitable means, such as an air-pump connected therewith. The entrance of air and impurities into the mercurial pump with 30 the mercury is thus avoided.

In order that my said invention may be clearly understood and readily carried into effect, I will proceed to describe the same more fully with reference to the accompanying 35 drawing, which shows a sectional elevation of my improved mercurial air-pump.

A is the head, which is connected by the pipe A' to the chamber B.

C is one of the fall-tubes.

40 D is a vessel into which the lower ends of the fall-tubes dip and from which the mercury flowing through the pump is returned to the head A for use over again by any suitable elevating apparatus.

45 E is the float, which is shown in the form of a tube or cylinder of glass, provided at its ends with cork or other stoppers e. These stoppers are perforated or otherwise formed to permit the mercury to flow through the 50 said float. The intervening space between the two stoppers contains particles of glass e' or other suitable substance that will not

have a detrimental effect on the mercury, the particles being of such a size and shape that there will be left between them innumerable 55 small interstices, through which the mercury will flow in a very fine state of division. I find that glass beads answer my purpose very well. The said float, together with the beads it contains, is made sufficiently buoyant to 60 float on the mercury within the head A, with its upper stopper a short distance below the inlet-nozzle a, through which the mercury enters the said head. The portion of the upper stopper that lies immediately below the 65 said inlet-nozzle is unprovided with perforations. When the inflow of the mercury becomes in excess of the outflow, the level of the mercury in the head A will rise, and thereby elevate the float and bring the imperforate 70 portion of its upper stopper against the said inlet-nozzle a, thus checking the inflow until the level of mercury in the said head falls again and allows the float to come out of contact with the said inlet-nozzle. The float is 75 also furnished with circumferential ribs or rings e² to act as guides.

The upper ends of the fall-tubes C are enlarged at c, where they enter the chamber B, and the mouths of these tubes are situated in 80 a position above that of the opening or openings a², through which the mercury enters the said chamber, so that in order for the mercury to descend the fall-tubes C it has to enter and rise in the said chamber until it 85 overflows into the fall-tubes. By this arrangement the flow of the mercury into the fall-tubes is rendered intermittent and enables the stream of mercury flowing through them to be in the condition of a succession of large 90 drops or pistons, which effectually act to exhaust the air or gas from the lamp-globes or other vessels that are for this purpose connected with the chamber B by the pipe B'.

A² is a stopper of glass or other appropriate 95 material by which the mouth of the head A is closed. It is made hollow to contain hygroscopic material, such as phosphoric anhydrid, the inlet-nozzle a extending vertically through said stopper and having a stop-cock 100 a' for controlling the flow of the mercury to the head A.

a² is another stop-cock on the stopper for controlling the passage a³, leading to an air-

pump, by which the space above the mercury in the head A is kept in a vacuous condition. The mouth of the head A is trumpet-shaped, so that a space a^4 is left around the portion of 5 the stopper entering said head to receive mercury or other substance to make a hermetic joint at this part.

The tube A' is made in straight sections, which are connected together by collars or 10 bands a^5 , composed of india-rubber or other appropriate material. The lower horizontal section is furnished with a stop-cock a^6 to enable the passage of the mercury in the head A and its tube to be stopped and permit the 15 mercury in the vertical section leading to the chamber B to be discharged into a vessel G when a stop-cock a^7 is opened. This enables the mercury in the head A and its tube to remain undisturbed while the other part of the 20 apparatus is being emptied of its mercury. When the apparatus is in operation, the stop-cock a^7 is closed and the stop-cock a^6 opened. The aforesaid vessel G is provided with a pipe g, furnished with a stop-cock g' , leading to an 25 apparatus for elevating the mercury in the vessel G to the head A or to a reservoir from which such head is supplied.

What I claim is—

1. In a mercurial air-pump having a head 30 for the mercury communicating with the vessels to be exhausted and with fall-tubes through which the mercury from said head descends to remove the air from the said vessels; the combination with the said head and 35 its inlet-nozzle, of a hollow float containing particles of material that will not detrimentally affect the mercury and through which the mercury will flow as it leaves the inlet-nozzle and thereby become comminuted, as 40 and for the purpose specified.

2. In a mercurial air-pump having a head for the mercury communicating with the vessels to be exhausted and with fall-tubes through which the mercury from said head

descends to remove the air from the said vessels; the combination with the said head and its inlet-nozzle, of a hollow cylindrical float containing glass beads held in place by perforated stoppers at the ends of the said cylindrical float and of guide-pieces on the exterior of said float, substantially as described and for the purpose specified. 45 50

3. In a mercurial air-pump having a head for the mercury communicating with the vessels to be exhausted and with fall-tubes 55 through which the mercury from said head descends to remove the air from the said vessels; the combination with the said head, of a hollow stopper to contain hygroscopic material, of an inlet-nozzle on said stopper, of a 60 float for regulating the passage of the mercury through the inlet-nozzle, and of means for comminuting the mercury entering said head, substantially as described and for the purpose specified. 65

4. In a mercurial air-pump having a head for the mercury communicating with the vessels to be exhausted and with fall-tubes through which the mercury from said head descends to remove the air from the said vessels; the combination with the said head, of a 70 hollow stopper to contain hygroscopic material, of an inlet-nozzle on said stopper, of a float for regulating the flow of mercury through said inlet-nozzle, of means for comminuting the mercury entering said head and of means for keeping the space in said head above the mercury in a vacuous condition, substantially as described and for the purpose specified. 75 80

In testimony whereof I have hereunto set my hand, in presence of two subscribing witnesses, this 14th day of April, 1899.

HIRAM STEVENS MAXIM.
